Primary Examiner — Andrew Kerr*Assistant Examiner* — Chariton Alexakis(74) Attorney, Agent, or Firm — Leydig Voit & Mayer, Ltd.(57) CLAIM

The ornamental design for a container for food packing, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a container for food packing showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The de-emphasized or half-tone areas in the drawings depict portions of the container fix food packing that form no part of the claimed design.
